L. F. CHANEY

GAS JET

Filed Nov. 12, 1920

UNITED STATES PATENT OFFICE.

LEE F. CHANEY, OF SPRINGFIELD, OHIO, ASSIGNOR TO THE CHANEY MANUFACTURING COMPANY, OF SPRINGFIELD, OHIO, A CORPORATION OF OHIO.

GAS JET.

Application filed November 12, 1920. Serial No. 423,657.

To all whom it may concern:

Be it known that I, LEE F. CHANEY, a citizen of the United States, residing at Springfield, in the county of Clarke and State of Ohio, have invented certain new and useful Improvements in Gas Jets, of which the following is a specification.

This invention relates to a blast burner or blow torch for operating within hollow or tubular bodies, and more particularly for use in the manufacture of floating or dairy thermometers, while fusing, sealing or otherwise operating upon the thermometer tube or stem, while inclosed within a casing tube of larger diameter.

The object of the invention is to simplify the structure as well as the means and mode of operation of blast burners for such purposes, whereby they will not only be cheapened in construction, but will be more efficient in operation, uniform in action, automatic and unlikely to get out of repair.

In the manufacture of floating or dairy thermometers it is the practice to fixedly attach or unite a thermometer tube within the enlarged float tube or casing, prior to filling and calibrating the tube and bulb. This capillary tube is then sealed within the casing tube before the casing or float tube is closed at its outer end. To assist such sealing the end of the capillary tube is fused within the tube or casing 2, and then drawn out or turned to close the capillary bore by touching a rod of glass or a bait to the end of the capillary tube while plastic. Inasmuch as the capillary tube is of somewhat less length than the casing or float tube, and terminates at a point inwardly spaced from the end of the outer tube, in effecting such sealing operation it is necessary to direct the blast or flame within the outer or casing tube against the end of the capillary tube therein. Much difficulty has been heretofore experienced thru the breakage of the casing or float tube during this operation, thru the uneven or ununiform heating of the outer tube causing the same to be cracked or shattered due to uneven expansion and contraction.

The present invention is designed to overcome this difficulty by providing for a cir-

culation of air within the casing or float tube during the operation of fusing the capillary tube therein and for the exhaustion of the heat generated and the products of combustion thereby protecting the casing or float tube against breakage.

With the above primary and other incidental objects in view as will more fully appear in the specification the invention consists of the features of construction, the parts and combinations and combinations thereof and the mode of operation or their equivalents as hereinafter described and set forth in the claims.

Referring to the drawing, Fig. 1 is a side elevation partly in section of a blast furnace to which the present invention has been applied. Fig. 2 is a top plan view of a portion of the burner showing the relation of the blast jet and exhaust conduit with the burner head and tube support. Fig. 3 is a detail sectional view of the pressure operated ejector by which the heated air and products of combustion as exhausted from the casing or float tube. Fig. 4 is a detail perspective view of the end of the exhaust tube showing the work locating head carried thereby.

Like parts are indicated by similar characters of reference throughout the several views.

While the present invention is herein shown and described in its application to the manufacture of float or dairy thermometers, it is to be understood that it is not limited to such application alone, but will find a wide range of usefulness in the metal working, plastic and heat treating arts. For this reason the disclosure herein is to be considered as illustrative of but one of several possible embodiments of the invention.

As disclosed in the accompanying drawings, 1 is the fuel supply conduit, thru which gas or other vaporous or hydro-carbon fuel is supplied to a burner head 2. This burner head 2 has been shown merely as an upturned or vertically disposed sleeve, having therein a loose packing 3, of steel wool or other fibrous heat resistant material. The supply of fuel to the burner head 3 is controlled by a cut-off valve 4, interposed in

the conduit 1 beneath the burner. Located in proximity to the burner 2 is a supply conduit 5 for fluid under pressure preferably air. This conduit is upturned at 6, and terminates in a tapered jet nozzle 7, in close proximity to and just above one side of the burner head 2, across which the jet nozzle discharges a jet of air or other fluid under pressure. The particular relation of the jet and burner may be modified to meet varying conditions. While the relationship shown in the drawing is one of practical application and commonly used, this relation may be varied from time to time and to this end the discharge portion 6 of the conduit is preferably curved and of some flexible or ductile material. This enables the portion 6 of the conduit to be bent to and from the burner head, to deliver its jet of compressed air as may be required. This jet blower in combination with the burner head forms a blast or blow torch, by which a concentrated flame of intense heat is directed laterally from the burner head. A control valve 8 is provided by which the air blast may be regulated. Leading from the air supply conduit 5, at a point in proximity to the jet conduit 6 is a discharge conduit 9, controlled by a cut-off valve 10, a portion of the supply of fluid under pressure is discharged to atmosphere at a point removed from the burner. Communicating with this discharge conduit 9 is an exhaust conduit 11, which is curved laterally, and extended substantially in line with the jet of flame directed by the air from the nozzle 7. The connection of the exhaust conduit 11 with the discharge conduit 9 is thru an injector connection shown in detail in Fig. 3. This comprises a T-shaped fitting 12 with the lateral arm of which the exhaust conduit 11 is connected. The initial section of the discharge conduit 9 projects within the transverse arm of the T connection 12 to a point beyond the lateral branch and terminates in a tapered jet nozzle 13, which discharges thru the connection 12, and into the outlet portion 14 of the conduit 9. The discharge of the jet of air under pressure thru the jet nozzle 13 within the T fitting 12 creates a suction thru the lateral branch of the fitting and exhaust conduit 11, whereby there is induced a current of air thru the exhaust conduit from the terminal thereof toward the fitting 12, thence outward thru the section 14 of the discharge conduit. This induced suction current draws the heated air and products of combustion out of the casing or float tube of the thermometer during the operation, and discharges them to atmosphere, thru the portion 14 of the discharge conduit.

The exhaust conduit 11 is provided at its intake terminal with a locating and sup-

porting head 15 for the work. This supporting head comprises a split sleeve, eccentrically secured upon the end of the exhaust conduit, with the split or slot 16 thereof, substantially aligned with the jet 70 discharged from the jet nozzle 7.

The work comprising the casing or float tube of the dairy thermometer with the capillary tube fixedly mounted therein, is positioned around the locating and supporting head 15, with the end of the capillary tube located within the slot 16 of such head. This brings the extremity of the capillary tube into position to be acted upon by the flame jet or blast from the burner. These tubes being of considerable length, it is obvious that the heating of the tubes will be concentrated or localized at their extremities. This ununiform heating and consequent unequal expansion and contraction, 85 has heretofore resulted in excessive losses from breakage, and has materially increased the cost of manufacture of such thermometers. In the present instance, however, so long as the blast is being directed upon the end of the capillary tube, in the casing or float tube the same supply of air or fluid under pressure by which the blast effect is achieved operates thru the ejector construction within the fitting 12 to induce a suction 95 draft thru the exhaust conduit 11, thereby drawing cool air into the mouth of the casing or float tube and causing a circulation about the point of operation, which serves to cool the tube and prevent overheating, 100 and at the same time this exhaust or suction draft, exhausts the tube of heated air and products of combustion. The result is that the heating effect of the blast or jet flame is confined to the end of the capillary tube 105 being fused, and extreme changes of temperature of the adjacent parts of the work is avoided, thereby equalizing the strain incident to expansion and contraction. The use of this automatic exhaust means in conjunction with the burner, has effected a material saving in material and work, and enabled thermometers of this character to be commercially produced in large quantities with great rapidity and uniform production. 110

While the head 15 has been shown and described as slotted and the capillary tube as being located within the slot, such construction is not at all essential. The supporting head 15 may be a continuous annular collar, devoid of any slot and the capillary tube may extend wholly within this support. By splitting the supporting head, it may be expanded or contracted radially to agree with 125 casing tubes of different diameters.

From the above description it will be apparent that there is thus provided a device of the character described possessing the particular features of advantage before enu- 130

merated as desirable, but which obviously is susceptible of modification in its form, proportions, detail construction and arrangement of parts without departing from the 5 principle involved or sacrificing any of its advantages.

While in order to comply with the statute the invention has been described in language more or less specific as to structural 10 features, it is to be understood that the invention is not limited to the specific details shown, but that the means and construction herein disclosed comprise but one of several modes of putting the invention into effect, 15 and the invention is therefore claimed in any of its forms, or modifications within the legitimate and valid scope of the appended claims.

Having thus described my invention, I 20 claim:

1. In a device of the character described, a burner, an air jet directing the flame from such burner within a hollow article operated upon, and a suction conduit extending within 25 the hollow article and exhausting therefrom the heated air and products of combustion.

2. In a construction of the character described, a jet burner and means for localizing the effect of the jet burner by establishing an air cooled zone in proximity to the point of operation of the jet burner including an exhaust conduit for simultaneous 30 operation with the burner extending to a point in proximity to the point of operation of the jet burner for withdrawing heated products of combustion and inducing the flow of a current of air about the point of operation.

3. The combination with a burner, of a jet nozzle for air under pressure in proximity thereto for directing the flame from said burner within a tubular body operated upon, and an exhaust conduit extending 45 within the tubular body in proximity to the jet of flame for withdrawing the heated air and gases.

4. The combination with a burner of a supply conduit for air under pressure, a 50 branch conduit leading therefrom discharging across the burner to afford a jet flame, a second branch conduit discharging to atmosphere, exhaust conduit extending into proximity with the point of operation of the jet flame and communicating with the last mentioned branch conduit, an injector fitting at the intersection of said exhaust conduit and the branch conduit whereby the discharge of air to atmosphere thru the 55 branch conduit will induce a suction thru the exhaust conduit to withdraw heated air and gases from the point of operation.

5. A burner, an exhaust conduit extending in proximity thereto, and a sleeve like 60 support carried by the exhaust conduit

about which a tubular body to be operated upon is positioned, the flame from said burner being directed within such tubular member substantially parallel with the exhaust conduit.

6. In a device for heat treating thermometers of the floating or insulated type, comprising a burner, an exhaust conduit extending in proximity to the burner and projecting within the casing tube of the thermometer, a split sleeve eccentrically mounted upon the exhaust conduit to be enclosed within the casing tube for positioning the tube in relation with the burner, the split in said sleeve being adapted to receive the capillary tube within the casing to insure proper positioning of the respective tubes in relation with the burner.

7. In a device for heat treating thermometers of the floating or insulated type, a burner, a tube supporting member adjacent to the burner, a cylindrical head carried by the supporting member, and insertable within the casing tube of the thermometer operated upon, said head having a longitudinal recess in one side thereof to receive the capillary tube within the casing tube to insure proper positioning of the tubes in relation with the burner.

8. In a device for heat treating thermometer tubes of the floating or insulated type, a supporting member having a head insertable within the casing tube, said head having therein an opening to receive the capillary tube and a burner in proximity to the tubes when engaged upon said head.

9. The herein described process of sealing the capillary tubes of floating or insulated thermometers consisting in directing a jet of flame upon the end of the capillary tube within the casing tube of such thermometer and simultaneously exhausting the air and heated gases from such casing tube.

10. The herein described process of heat treating glass tubes or other hollow bodies 110 consisting in directing a flame within the tube and simultaneously effecting a circulation of air within the tube.

11. The herein described process of heat treating glass tubes or other hollow bodies 115 consisting of directing a flame within the hollow body and simultaneously drawing thereinto a supply of air.

12. In an apparatus of the character described, a blast burner, a conduit for supplying air under pressure to said blast burner, and a branch conduit extending from the air supply conduit to a point in proximity to the point of operation of the blast burner for inducing a circulation of air about the point of operation of the burner and dissipation of the products of combustion, whereby the effect of the blast burner will be localized.

13. In an apparatus of the character described, the combination with a jet burner 120

of a ventilating conduit extending into proximity to the point of operation of the jet burner and means for inducing a flow of air through said conduit whereby the heated products of combustion will be dissipated and the effect of the jet burner localized.

In testimony whereof, I have hereunto set

my hand this 5th day of November, A. D. 1920.

LEE F. CHANEY.
